UNITED STATES PATENT OFFICE.

GUSTAV A. SCHILLINGER, OF CHICAGO, ILLINOIS, ASSIGNOR TO JONES NATIONAL FENCE COMPANY, OF COLUMBUS, OHIO, A CORPORATION OF OHIO.

FIREPROOF CONSTRUCTION.

SPECIFICATION forming part of Letters Patent No. 722,460, dated March 10, 1903.

Application filed May 20, 1901. Serial No. 61,141. (No model.)

To all whom it may concern:

Be it known that I, GUSTAV A. SCHILLINGER, a citizen of the United States, and a resident of Chicago, in the county of Cook and State of Illinois, have invented certain new and useful Improvements in Fireproof Construction, of which the following is a specification, reference being had to the accompanying drawings, and to the letters of reference marked thereon, which form a part thereof.

This invention relates to a fireproof construction and as shown more particularly in relation to a fireproof floor and ceiling construction, though adaptable for many other purposes.

The invention has for its object a construction at once fireproof, light, and strong and of great rigidity and durability as compared with some constructions heretofore used.

The invention embraces many novel features; and it consists of the matters hereinafter described, and more fully pointed out and defined in the appended claims.

In the drawings, Figure 1 is a fragmentary plan view of one form of netting embodied in my invention. Fig. 2 is a vertical section of one form of my invention. Fig. 3 is a vertical section of another form of my invention. Fig. 4 is a fragmentary plan view of another form of netting embodied in my invention. Fig. 5 is a plan view of one of the junction-plates for the netting illustrated in Fig. 4 before the lugs are bent up. Fig. 6 is a section taken on line 7 7 of Fig. 4. Fig. 7 is a section taken on line 8 8 of Fig. 4. Fig. 8 is a plan view of a blank for a clip embodied in my invention. Fig. 9 is a side elevation of the same completed. Fig. 10 is a plan view of a floor and ceiling construction embodying my invention. Fig. 11 is a vertical section of the same. Fig. 12 is a fragmentary plan view of a floor and ceiling construction embodying my invention adapted for thermal insulation. Fig. 13 is a vertical section of the same. Fig. 14 is a plan view of a blank for another form of clip. Fig. 15 is a vertical section of the same completed. Fig. 16 is a fragmentary side elevation of a column constructed in accordance with my invention.

Fig. 17 is a transverse section of the same.

In carrying out the invention and describing the same first in connection with a floor and ceiling construction, A indicates I-beams of ordinary form supported in the usual manner in the wall of a building on posts or in any desired manner. Across the tops of the I-beams are laid carrying-rods B, which are bent at their ends, forming hooks which embrace the upper oppositely-directed flange of adjacent I-beams. The I-beams throughout the entire width and length of the building are so connected at suitable distances apart by means of said carrying-rods, upon which are laid strips or sheets of wire-netting, similar to that illustrated in Figs. 1 and 4, or other desired form of reticulated material. Said netting may be constructed of rods or large wires C', some of which lie across the carrying-rods and act to distribute pressures from above. In the form of netting illustrated in Fig. 1 the netting is composed of longitudinal and transverse wires C' and C², both of which are bent at their point of crossing and are laced through washer-like disks C³, which lie over the transverse wires C² and under the longitudinal wires C'. In the form illustrated in Fig. 4 disks C⁴ of metal are provided at the intersections of said wires, said disks having diametrically opposite lugs c c, which are apertured and turned up and through which the longitudinal wires C' pass over the transverse wires C², as shown in Figs. 6 and 7. When the metallic supporting-framework is thus prepared, the I-beams may be incased on their under sides with the usual board mold, and concrete may be filled therein and tamped to fill the spaces between beams and packed solidly around the carrying-rods B and into the meshes of the netting. When the concrete hardens, the molds may be removed and a facing coat of cement or asphalt or other material spread on the under surface or ceiling side of the concrete and the upper surface finished to form a floor.

In the form illustrated in Figs. 1 and 2 a plane ceiling is provided, supported on supplemental carrying-rods B², which are bent upwardly at their ends which rest on the adjacent lower flanges of the I-beams. In the form illustrated in Fig. 2 the carrying-rods B

or some of said carrying-rods are bent downwardly and beneath the carrying-rods B^2 and act to support the same centrally. Wire-netting may be used, if preferred, in constructing the ceiling, the same being wired to the supplemental carrying-rods B^2 or laid upon the same and the concrete filled in in the usual manner, leaving a space between the floor and ceiling, which space may be left as a dead-air space or may be filled with cinder or other poor conductor of heat, as preferred. The form illustrated in Fig. 3 is similar to that shown in Fig. 2, with the exception that the supplemental carrying-rods B^2 are wired to the carrying-rods B by one or more strands of wire B' , thereby rigidly supporting the ceiling from the floor above.

Obviously a construction embodying my invention may be employed in fireproof construction in many different ways, and in many instances, such as the construction of warehouses or the like, it may be neither necessary nor desirable to have a ceiling. In such cases the carrying-rod illustrated in Figs. 12 and 13 by B^3 is hooked at its ends to engage over the I-beams, as before described, and bent downwardly or depressed intermediate of said I-beams, the netting is laid thereon, as before described, and the filling of concrete is applied. The ends of said carrying-rods are turned downwardly and outwardly, forming a support b for the part of the concrete which abuts against the web of the I-beams. Before applying the concrete a platform or mold of boards is supported between the I-beams a desired distance below the carrying-rods. The concrete when applied is thereby given a plane under surface. When the concrete is set or hardened, the upper coating of asphalt or other material may be applied to form a smooth finish for the floor or a floor of any desired kind laid. In this construction the supplemental carrying-rods B^4 and the clips D^2 would of course be dispensed with. Figs. 10 and 11 show another form of my ceiling and floor construction in which supplemental carrying-rods B^4 are provided with hooked ends adapted to engage over the top of the I-beams and beneath the outer flanges at the top. Said rods are of sufficient length to extend downwardly along said I-beams and across between adjacent I-beams, as shown in Fig. 11. When said supplemental carrying-rods are in position, a strip of wire-netting C is placed thereon with its ends thereof extending upwardly beneath the carrying-rods B^3 against the upwardly-extending portions of the supplemental carrying-rods, as shown in Fig. 11, thereby forming a pocket to receive and support the concrete which is bedded thereon, as before described. Obviously in this form of my construction it would be difficult to secure the concrete in the spaces beneath the I-beams. For the purpose of rigidly securing the same thereto I provide clamps or clips, any of several forms of which may be used, that shown in Figs. 8 and 9 con-

sisting of a band of strap metal slit longitudinally from the ends to near the center to form the tongues d^2 d^2 , which are bent upwardly to form hooks to engage the bottom flanges of the I-beams. The lateral portions of said straps are turned downwardly and outwardly to form the support d^3 d^3 , the use of which is clearly illustrated in Fig. 18, in which the general construction is similar to that heretofore described for Fig. 12, with the exception that the end portions of the supplemental carrying-rods B^4 adjacent to the webs of the I-beams are bent inwardly toward the I-beams, thereby slightly arching the ends of said rods and causing the weight of the ceiling to be in part supported by a portion of the concrete extending upwardly adjacent to the web.

The construction illustrated in Figs. 12 and 13 is similar to that shown in Figs. 10 and 11, with the exception that means are shown for insulating the floor from changes of temperature and also a modified form of construction of a concrete clip d^4 , the construction of which is more clearly illustrated in Figs. 14 and 15, in which a piece of strap-iron is bent upwardly to form the hooks D^2 D^2 , adapted to secure the clips to the bottom of the I-beams, and the tongues d^4 d^4 are bent downwardly and outwardly to engage the concrete. The concrete is secured in position, as before described, and when the same is set a plurality of strips of felt or other suitable material are laid one upon the other, covering the entire floor, and a layer of asbestos preparation is spread over the same. Above this are laid other strips of felt or the like, and on this may be secured the floor, either of asphalt, wood, or other material, as desired. Obviously, if preferred, more than two layers of felt or other material may be employed, and each layer may be one or more thicknesses in depth.

Among the many purposes to which my invention is adaptable is a column construction, (illustrated in Figs. 16 and 17,) which may properly be considered a part of my invention. In this case a central column may be cast or constructed, hollow, as shown, of structural-iron plates and Z-irons and having laterally-projecting flanges at the corners. On said plates clips D^3 are secured, similar to any of the clips hereinbefore described and having outwardly and laterally directed ends to engage the concrete or other filling material. Carrying-rods B^5 are provided, the ends of which extend around and hook over the opposite flanges remote therefrom, as shown in Fig. 26, and the ends of which may be turned outwardly to form the supporting-hooks b^5 b^5 for the concrete or filling. About the extended ends of said clips and the hooks d^5 d^5 wire-netting or other reticulated material is tightly drawn, as shown in Fig. 25, and the concrete firmly bedded thereon in a manner similar to that already described, thus building up a column of uniform size and of great strength as compared with weight. The ex-

terior of said column may be finished with a coating of any desired kind—such as asphalt, plaster, or other desired material—to afford a finish.

5 Obviously my invention may be applied to many other purposes than herein described, and many details of construction may be modified without departing from the principle of my invention.

10 I claim as my invention—

15 1. In a fireproof construction, the combination with supporting-beams, of carrying-rods bent near their ends to form hooks which engage over the beams, the ends of said rods projecting beyond the beams and adapted to support concrete or the like, a sheathing of reticulated material on the carrying-rods and a filling of concrete or like material bedded on the carrying-rods and reticulated material.

20 2. In a fireproof construction the combination with supporting-beams of carrying-rods thereon, hooked ends on said carrying-rods which engage over said beams, the extremity of said rods projecting laterally of the beam,

25 supplemental carrying-rods also supported on said beams and at the bottom thereof, reticulated material on said carrying-rods and on said supplemental carrying-rods and a filling of concrete or the like investing the frame thus formed.

30 3. In a fireproof construction the combination with supporting-beams of carrying-rods engaging on and partly around said beams, supporting-hooks formed by the outwardly-directed ends of the carrying-rods, a reticulated material covering said carrying-rods, supplemental carrying-rods supported from said beams opposite the carrying-rods, reticulated material covering the inner sides of said

35 supplemental carrying-rods and a concrete filling surrounding said beams, carrying-rods and supplemental rods, clips supported on said beams and projecting ends on the clips adapted to engage the concrete to the beam.

40 4. In a device of the class described the combination with a plurality of beams, of carrying-rods, hooks formed in said rods adjacent to the ends and engaging over said beams, the ends of said carrying-rods beyond the hooked portions extending outwardly beyond the beams and approximately parallel with the carrying-rods.

45 5. In a fireproof construction the combination with supporting-beams, of carrying-rods supported thereon, hooks formed in said rods adjacent to each end portion adapted to engage over said beams, supporting means formed by the end portions of said rods beyond said hooked parts and extending laterally beyond the beams and reticulated material on said carrying-rods.

50 6. In a fireproof construction the combination with two or more I-beams, of carrying-rods supported on adjacent beams hooks in said rods adjacent to the ends thereof engaging over the outwardly-directed flanges of said beams, the ends of said carrying-rods form-

ing supports directed laterally of the beams, reticulated material supported on said carrying-rods and beams, and concrete or the like 70 bedded on said beams, carrying-rods and reticulated material and supported beneath the upper flanges of the I-beams on the ends of said carrying-rods.

7. In a floor and ceiling construction the 75 combination with the I-beams of a floor-frame, of carrying-rods supported thereon, hooked portions adjacent to the ends on said carrying-rods which engage on opposite sides of the I-beams, supplemental carrying-rods also 80 engaging with hooked ends over the tops of said I-beams, and extending downwardly along said I-beams and transversely between the same, reticulated material on said carrying-rods and supplemental carrying-rods the 85 ends of that on the latter extending upwardly along the beams, concrete or the like supported on the framework thus formed, clips engaged on the bottoms of said I-beams and having hooked projections to engage in the 90 concrete and supports formed by the ends of said carrying-rods acting to engage the concrete beneath the top flanges of the I-beams and support the same.

8. A reticulated structure for the purpose 95 specified comprising two series of parallel wires or rods intersecting at approximately right angles with each other and bent at the intersection thereof, a metal plate secured beneath said points of intersection, apertured 100 lugs disposed oppositely on said plate and through the apertures of which the uppermost of said wires passes thereby binding the lower wire or rod to the plate.

9. In a fireproof construction, the combination with supporting I-beams, of carrying-rods and supplemental carrying-rods supported in alinement with the tops of the I-beams and with the bottom thereof respectively and having hooked ends which engage 110 upon the I-beams and a tie connecting said carrying-rods and supplemental carrying-rods intermediate of their ends.

10. In a fireproof construction the combination with supporting I-beams, of carrying-rods and supplemental carrying-rods supported in alinement with the top of the I-beams and with the bottom thereof respectively and having hooked ends which engage 115 upon the I-beams and a tie connecting said carrying-rods and supplemental carrying-rods intermediate of their ends, reticulated material supported upon the carrying-rods and supplemental carrying-rods and a filling of concrete or the like investing the frame 120 thus formed.

11. In a fireproof construction the combination with supporting I-beams, of carrying-rods supported thereon and engaging over said I-beams with hooks adjacent to their 130 ends, reticulated material on said carrying-rods, concrete or the like engaged on said I-beams, carrying-rods and reticulated material, a plurality of layers of felt or the like

supported on said concrete and separated from each other by fireproofing and insulating material and a floor constructed on the uppermost of said layers of felt or the like.

- 5 12. In a construction of the class described, a metallic rod formed adjacent to each end with an inwardly-directed hook the extremities of said rod being directed approximately parallel with the rod and outwardly.
13. In a fireproof construction, the combination with supporting-beams of carrying-rod supported thereon and engaging over the beams with hooks adjacent to their ends, reticulated material on the carrying-rod, con-

crete or the like supported on the beams, carrying-rod and reticulated material and a plurality of layers of felt paper or the like supported on the concrete and separated from each other by insulating material and a floor on the uppermost of said layers.

15
20 In testimony whereof I have hereunto subscribed my name in the presence of two subscribing witnesses.

GUSTAV A. SCHILLINGER.
